INVENTOR,

UNITED STATES PATENT OFFICE.

OSCAR M. WOLFF, OF CHICAGO, ILLINOIS.

DESIGN FOR A BOTTLE.

SPECIFICATION forming part of Design No. 35,166, dated October 8, 1901.

Application filed September 11, 1901. Serial No. 75,106. Term of patent 7 years.

To all whom it may concern:

Be it known that I, OSCAR M. WOLFF, a citizen of the United States, and a resident of Chicago, in the county of Cook and State of Illinois, have invented and produced a new and original Design for Bottles, of which the following is a specification, reference being had to the accompanying drawings, forming a part thereof.

16 In the accompanying drawings, Figure 1 is a front elevation of a bottle made according to my new design. Fig. 2 is a rear elevation of same. Fig. 3 is a top plan view. Fig. 4 is a longitudinal section along the line 4-4 of Fig. 1. Fig. 5 is a transverse section on the line 5-5 of Fig. 1.

The leading or material feature of my design consists of a bottle hexagonal in cross-section, having in each of its alternate sides 20 a niche or depressed panel which is angular in cross-section. The main body of the bottle shown is a hexagonal prism, having a flat base 1. The alternate sides 2 are about twice the width of the intermediate sides 3,

and each of the sides 2 has therein an angular niche extending from a point 7 near the bottom to a point 8 near the top of such sides. Each of the niches may be described as consisting of two panels 9, extending inwardly from the lateral bounding edges 10 of the 30 sides 2 and meeting at an angle in the line 11. The panels 9 terminate in fillets at 7 and 8.

The neck 12 of the bottle is cylindrical and connects with the prismatic body of the bottle by a conical shoulder 13 and is surrounded by a head 14.

What I claim as new, and desire to secure by Letters Patent, is—

The design for a bottle, substantially as 40 herein shown and described.

Signed by me at Chicago, this 9th day of September, 1901.

OSCAR M. WOLFF.
